UNITED STATES PATENT OFFICE.

ARTHUR KITSON, OF PHILADELPHIA, PENNSYLVANIA, ASSIGNOR TO THE KITSON HYDROCARBON HEATING AND INCANDESCENT LIGHTING COMPANY, OF SAME PLACE AND CHARLESTON, WEST VIRGINIA.

THERMOSTATIC VALVE FOR VAPOR-BURNERS.

SPECIFICATION forming part of Letters Patent No. 665,115, dated January 1, 1901.

Application filed March 23, 1900. Serial No. 9,852. (No model.)

To all whom it may concern:

Be it known that I, ARTHUR KITSON, a subject of the Queen of Great Britain, and a resident of Philadelphia, (Germantown,) county of Philadelphia, State of Pennsylvania, have invented certain new and useful Improvements in Thermostatic Valves for Vapor-Burners, of which the following is a specification.

10 My invention relates to vapor-burning apparatus in general; and more specifically it consists of an improved form of thermostatically-operated valve for controlling the admission of fluid hydrocarbons to the vaporizing-chamber of such apparatus. It is desirable in structures of this kind to reduce the number of parts as much as possible and to employ iron or steel instead of other high-priced materials. If iron or steel, however, is used 15 for the thermostatically-operated apparatus, it is apt to be slow in its action, being protected by the surrounding walls of the vaporizing tube or chamber from the heat of the burner, and consequently the initial expansion of the vaporizing-tube itself produces a premature opening of the valve. I have discovered, however, that these difficulties can be overcome by so forming the steel or iron rod which constitutes the valve-operating apparatus that for a considerable portion of its 20 length it will be in intimate contact with the walls of the vaporizing-tube, and thereby receive the necessary amount of heat to cause it to share in the initial expansion of the entire apparatus and maintain the valve closed until a thorough heating of the whole apparatus shall have prepared it for proper vaporization of the admitted oil.

The preferred form of apparatus embodying my invention is illustrated in the accompanying drawing, in which an ordinary vaporizing-tube 1 is shown extending across the chimney 2 of the vapor-burning apparatus, a portion of said chimney being shown 25 in dotted lines. At one end of the vaporizing-tube is a casting 3, having a valve-seat 4 formed therein and an inlet passage-way 5. At the other end of the vaporizing-tube is a casting 6, having a discharge-orifice 7 and a connecting passage-way 8 formed there-

in. A rod 9, of steel or iron, being of the same material of which the vaporizing-tube 1 is composed, is mounted at one end in the casting 6 and has an adjustable extension 10, forming a valve-plunger which coöperates with 55 the valve-seat 4 in the casting 3 at the inlet end of the vaporizing-tube. A determinate portion of the length of the rod 9 is bent, as indicated at 11, so as to be in contact with the walls of the vaporizing-tube 1. Preferably this bent portion 11 is at the central or middle portion of the vaporizing-tube, and it is preferably so bent as to come in contact with the lower wall of the vaporizing-tube. It will therefore be seen that the operation of the valve may be determined and varied by shortening or lengthening that portion of the rod in contact with the tube.

If desired, the valve-plunger 10 may have a squared end portion 12 at its extremity, to 70 which a key may be applied for purposes of adjustment after removing the screw-threaded cap 13 on the end of the casting 3.

The fuel-supply of fluid hydrocarbon is supposed to come from the tank 14 under 75 pressure through the tube 15, controlled by the valve 16.

The method of operation of my invention is as follows: When the lamp is started into operation, the valve 16 is opened, but the 80 valve 10 normally closes access to the vaporizing-tube. The vaporizing-tube is given an initial heating by a jet of gas or alcohol flame or other means, and the greatest amount of heat is usually applied to the middle portion 85 of the vaporizing-tube. Consequently the vaporizing-tube expands lengthwise; but the portion 11 of the rod 9 being in immediate contact with the wall of the vaporizing-tube also receives sufficient heat to cause it to expand at the same rate, and the valve-plunger 90 10 is held down to the seat 4 until the vaporizing-tube 1 becomes thoroughly heated throughout its entire length by conduction. The end portions of the rod 9, being out of 95 contact with the walls of the vaporizing-tube, are protected from the heat and fail to expand at the same rate as do the surrounding portions of the vaporizing-tube walls. Consequently by the time the vaporizing-tube has 100

become thoroughly heated the valve-seat 4 has moved away slightly from the valve-plunger 10 and oil is admitted in small quantities to the vaporizing-tube, where it is vaporized 5 and discharged through the orifice 7. When the lamp is turned off by closing the valve 16, the vaporizing-tube 1 will contract to a greater extent than the rod 9 and the valve-plunger 10 will be forced down onto the seat 4 and the 10 valve again closed. Adjustment of the valve is secured by removing the cap 13 and turning the plunger 10 by means of a key applied to the squared end 12.

The advantages of my invention comprise 15 its simplicity, which arises from the fact that it requires but two extra parts 9 and 10, which may be installed in the ordinary vapor-tube without serious modification thereof, the further fact that only iron or steel is used, and 20 its ease of adjustment by simple rotation of the threaded connection between parts 9 and 10 or by bending the part 9 so as to vary the extent of the same which shall be in contact with the tube-walls. Moreover, the thermostatic-rod 9, being mounted in a cup-shaped 25 socket in the casting 6 and not in a perforation which extends through said casting or other end portion of the vaporizing-tube, there is no liability to leakage of vapor, which 30 might otherwise be caused by loosening of the parts through expansion and contraction and the stresses to which the connections are subjected by the operation of the thermostat.

It is evident, of course, that various changes 35 could be made in the details of construction illustrated without departing from the spirit and scope of my invention, so long as the relative arrangement of parts or the principle of operation disclosed is preserved. The rod 40 9 may be of different form, so long as a portion of its surface is in intimate contact with the walls of the vaporizing-tube and other portions are out of contact therewith. Other means of adjusting the valve might be employed and the end castings 3 and 6 might be 45 made of different form; but these and similar modifications would not change the principle of operation and the resulting construction would still be within the limits of my invention.

Having therefore described my invention, what I claim as new, and desire to protect by Letters Patent, is—

1. The combination of the vaporizing-tube, 55 the valve located in one end thereof and the thermostatic-valve-actuating apparatus located in the interior of the tube and in contact with the walls of the tube at the point of highest temperature.

2. The combination of the vaporizing-tube, 60 the valve located in one end thereof and the thermostatic-valve-actuating apparatus, consisting of a rod composed of the same metal as the tube, located in the interior of the tube and in contact with the walls of the tube at 65 only the point of highest temperature.

3. The combination of the horizontal vaporizing-tube, the valve located in one end thereof, and the thermostatic-valve-operating apparatus comprising a rod extending from 70 one end of the tube to the other and having its middle portion in contact with the lower portion of the wall of the vaporizing-tube.

4. The combination of the horizontal vaporizing-tube, the valve located in one end 75 thereof, and the thermostatic-valve operating apparatus comprising a rod extending from one end of the tube to the other and having its middle portion bent down in contact with the lower portion of the wall of the vaporizing-tube. 80

5. The combination of the horizontal vaporizing-tube, the valve located in one end thereof, and the thermostatic-valve-operating apparatus comprising a rod extending from 85 one end of the tube to the other and having its middle portion bent down in contact with the lower portion of the wall of the vaporizing-tube, said rod being formed of the same metal as the vaporizing-tube. 90

6. The combination of a vaporizing-tube, a casting provided with a discharge-orifice and communicating passage-ways connected to one end of the tube, a second casting provided with inlet passage-ways and a valve-seat connected to the other end of the tube, and a valve-plunger mounted in a cup-shaped 95 socket in the first casting and co-operating with the valve-seat in the second casting.

7. The combination of a vaporizing-tube, a 100 casting provided with a discharge-orifice and communicating passage-ways connected to one end of the tube, a second casting provided with inlet passage-ways and a valve-seat connected to the other end of the tube, and a valve-plunger mounted in a cup-shaped 105 socket in the first casting and co-operating with the valve-seat in the second casting, said valve-plunger having a determinate portion of its length in contact with the walls of the 110 vaporizing-tube.

Signed at New York, N. Y., this 17th day of March, 1900.

ARTHUR KITSON.
